UNITED STATES PATENT OFFICE.

BENJAMIN F. INGE, OF ROANOKE, VIRGINIA.

SOCKET FOR CONNECTING PACKAGE-TIERS.

1,030,661.

Specification of Letters Patent. Patented June 25, 1912.

Application filed February 17, 1912. Serial No. 678,177.

To all whom it may concern:

Be it known that I, BENJAMIN F. INGE, a citizen of the United States, residing at Roanoke, in the county of Roanoke and State of Virginia, have invented new and useful Improvements in Sockets for Connecting Package-Tiers, of which the following is a specification.

This invention relates to sockets designed preferably for package tiers and has for an object to provide companion sockets which may be readily secured to the terminals of a tying element and relatively arranged whereby they can be securely connected together to hold the tier in operative position around the package.

In the drawing forming a portion of this application and in which like letters of reference indicate similar parts in the several views, Figure 1 is a perspective view of the binder showing its application to a package of letters. Fig. 2 is a plan view of the binder. Fig. 3 is a section through the attaching means. Fig. 4 is a plan view of the blank from which one of the sockets of the fastening means is formed.

The binder comprises preferably a spring 1 or similar elastic tying element which is capable of being wrapped about the package as shown in Fig. 1. Means 2 are employed for operatively connecting and securing the opposite terminals of the spring 1 together and as illustrated this means comprises identical socket members 3 which are each formed from a blank A shown in

Fig. 4. The socket members are preferably of cylindrical form and each receives therein one terminal of the spring 1. Each socket member has its walls provided with an integral tongue 4 which is bent over the outer open end of the socket so as to present an eye 5. The terminal of the tongue is soldered or otherwise suitably secured to the inner walls of the socket member and then bent to present a loop 7. Terminals of the spring 1 are provided with suitable hook portions 8 which are engaged in the loops 7 as shown in Fig. 3 whereby the adjacent terminals of the spring are maintained in the socket members. The eye portion 5 of one of the socket members is provided with a snap hook 9 which is adapted to be engaged in the eye 5 of the other socket member as shown in Fig. 1 whereby the binder is held in tied position around the package.

I claim:

A socket comprising a hollow member constructed of a single piece of material and provided with a bent portion forming a loop at one end of the member and having its terminal extended into the member and formed therewith to provide an eye.

In testimony whereof I affix my signature in presence of two witnesses.

BENJAMIN F. INGE.
